United States Patent Office

Des. 197,279
Patented Jan. 7, 1964

197,279

PANEL TYPE TELEPHONE

Keith D. Bartley, New Shrewsbury, N.J., and Henry Dreyfuss, South Pasadena, Calif., assignors to Bell Telephone Laboratories, Incorporated, New York, N.Y., a corporation of New York

Filed Oct. 30, 1962, Ser. No. 72,313

Term of patent 14 years

(Cl. D26—14)

F/G. 1

FIG. 2

FIG. 3

FIG. 1 is a front perspective view of a panel type telephone showing our new design;

FIG. 2 is a top plan view, to a reduced scale; and

FIG. 3 is a side elevational view thereof, to a reduced scale.

The dominant features of our new design reside in the portion shown in solid lines on the drawing.

We claim:

The ornamental design for a panel type telephone, as shown and described.
